UNITED STATES PATENT OFFICE.

JOSEPH SIEGEL, OF DETROIT, MICHIGAN, ASSIGNOR TO AMERICAN LADY CORSET COMPANY (INC.), OF DETROIT, MICHIGAN, A CORPORATION OF MICHIGAN.

GARMENT.

Application filed February 24, 1925. Serial No. 11,276.

The invention relates to garments and has for one of its objects the provision of a garment comprising upper and lower dress elements which are detachably secured to each other at a plurality of peripheral points, whereby they may be retained in their proper relative positions and also detached from each other to permit of cleaning the same. Another object is the provision of a garment comprising upper and lower dress elements overlapping and detachably secured to each other to permit adjusting the garment to the height of the wearer. A further object is the provision of a garment comprising a girdle and a brassière, the latter surrounding a portion of the former and being detachably secured thereto at both the front and rear.

With these as well as other objects in view the invention resides in the novel features of construction and combinations and arrangements of parts as more fully herein-after set forth.

In the drawings:

Figure 1 is a perspective view of a garment embodying my invention;

Figure 2 is a rear elevation thereof;

Figure 3 is a cross section on the line 3—3 of Figure 2;

Figure 4 is an enlarged inner side elevation partly broken away showing a portion of the garment.

1 and 2 designate respectively the upper and lower dress elements of the garment. The upper dress element is a brassière adapted to retain the figure of the wearer. The lower dress element is a girdle which is also adapted to retain the figure of the wearer, this girdle being provided with longitudinally extending stays in its front and rear portions including the stays 3 in the upper central part of its front portion and the stays 4 in its rear portion adjacent to the side elastic webbings 5 of the lower portion. Both the brassière and girdle open at one side of the garment, the openings preferably registering with each other and the edges of the brassière and girdle at these openings being suitably secured to each other as by means of hooks and eyes.

50 The brassière 1 preferably surrounds the upper portion of the girdle 2 and this brassière is detachably and adjustably secured to the girdle at both the front and rear so that the garment formed thereby may be adjusted to the height of the wearer and secured in

their proper relative positions and at the same time the brassière and girdle may be separated to permit cleaning. As shown the brassière is secured to the girdle by means of the string 6 at the front of the garment 60 and the strings 7 and 8 at the rear of the garment. These strings are preferably secured to the brassière and extend through a pair of eyelets 9 secured to the girdle, the ends of the strings being located inside the 65 girdle. The eyelets through which the strings 6 pass are located below and adjacent to the stays 3 while the eyelets through which the strings 7 and 8 pass are located above and adjacent to the stays 4. 70

The brassière 1 is provided with the shoulder straps 10 and the girdle 2 has secured thereto the hose supporters 11 which are located adjacent to the elastic webbings 5. Also the girdle opening is adjacent to one 75 of the elastic webbings.

From the above description it will be seen that I have provided a garment comprising upper and lower dress elements which are detachably and adjustably secured to each other at a plurality of peripheral points so that these elements may be adjusted relative to each other to fit the height of the wearer and will also retain their proper relative positions. Furthermore, the dress elements 85 may be separated to permit cleaning.

What I claim as my invention is:

1. A combination garment comprising a lower dress section provided with a longitudinally extending stay in its upper front 90 portion and an upper dress section overlapping said lower dress section and means for adjustably securing said dress sections to each other, including a securing element located adjacent to and below said stay. 95

2. A form retaining garment comprising a girdle section and a brassière section, said brassière section surrounding a portion of said girdle section, longitudinally extending stays in said girdle section and strings for adjustably securing the front portions of said girdle section and brassière section to each other, said strings being arranged below the said stays. 100

3. A form retaining garment comprising an upper brassière section and a lower girdle section, said sections overlapping for a portion of their length, relatively long longitudinally extending stays in the rear portion of the girdle section, relatively short longi- 110

itudinally extending stays in the front portion of the girdle section, and a plurality of securing elements for adjustably securing said sections to each other, said securing elements being located below the relatively short stays and above the relatively long stays in the girdle section, and in abutting engagement with the ends of the said stays for preventing buckling of that portion of the girdle section which is above the lower edge of the brassière section.

4. In a form retaining garment, the combination of a lower form retaining section,

an upper form retaining section surrounding a portion of said lower form retaining section, means for adjustably securing said sections to each other and a member carried by the lower form retaining section, having one end in abutting engagement with the said securing means for bracing that portion of the lower form retaining section which is surrounded by the upper form retaining section.

In testimony whereof I affix my signature.

JOSEPH SIEGEL.
